UNITED STATES PATENT OFFICE.

ROGER LOCKE AVERY, OF CHICAGO, ILLINOIS.

GAS-CONTROLLER.

1,000,485.

Specification of Letters Patent. Patented Aug. 15, 1911.

Application filed August 24, 1910. Serial No. 578,684.

To all whom it may concern:

Be it known that I, ROGER L. AVERY, a citizen of the United States, and a resident of the city of Chicago, county of Cook, and

5 State of Illinois, have invented certain new and useful Improvements in Gas-Controllers, of which the following is a specification.

My invention relates to improvements in 10 controllers for gas burners.

At the present time great waste of gas is occasioned in gas-stoves or ranges through failure in turning off the gas supplying a gas burner when the latter is not actually in 15 use. For instance, in the course of preparation of a meal it is common practice for the housewife or cook to turn on the gas at the commencement of preparation and to permit it to burn until the completion of preparation, that is, during interchanging of utensils upon the stove in the course of cooking various articles for the meal, time is never 20 taken to turn off the gas when a utensil is lifted from heating position thereover and 25 to turn it on again and light it when another is arranged in its place. The loss of time and the inconvenience incident to resorting to such practice evidently is too great to result in any ultimate economy or benefit.

30 It is the object of my invention to provide a controller for gas burners which will be of such design and construction as to be adapted, through the medium of the weight of an article or utensil arranged in position for 35 heating over the burner coöperating therewith, to be operated so as to permit of the free flow of gas to the latter; and upon the removal of the article therefrom to be automatically operated to instantly shut off the 40 supply of gas thereto.

A further object is the provision of a controller of the character mentioned which will be positive and quick-acting in operation and of simple and effectual construction.

45 Other objects will appear hereinafter.

With these objects in view my invention consists in a gas controller characterized as above mentioned and in certain details of 50 construction and arrangement of parts all as will be hereinafter fully described and particularly pointed out in the appended claims.

My invention will be more readily understood by reference to the accompanying 55 drawings forming a part of this specification and in which,

Figure 1 is a simple sectional view of a gas-stove and burner equipped with a controlling device embodying the preferred form of my invention, Fig. 2 is an enlarged detail central section of a fitting and a lever coöperating therewith included in my invention, Fig. 3 is a section on line $x-x$ of Fig. 2, Fig. 4 is a section on line $y-y$ of Fig. 2, Fig. 5 is a section on line $z-z$ of Fig. 2, and Fig. 6 is a section on line $w-w$ of Fig. 1.

Referring now to the drawings 1 indicates a gas-stove or range of any ordinary or preferred construction, and 2 the top plate 70 thereof. Arranged in the hole 3 of the top 2 is the usual utensil supporting web or grate 4 upon which, when the device is used, is arranged the article or utensil to be heated. Centrally arranged below the opening 75 3, the same being supported upon depending hangers 5 secured to the plate 2 is a burner 6.

7 indicates the usual manifold which extends along the front side of the stove and which is connected with any suitable source 80 of fuel supply. The passage 8 leading rearwardly from the manifold is governed by a needle valve 9 which is threaded in said manifold, the inner end thereof being adapted to fit in a valve fitting 10, in which position the passage 8 will be entirely closed. 11 indicates a hand piece for operating said valve. Threaded into the manifold 7 at the rearward side thereof is a fitting 12 having a fuel passage 13 therein communicating 90 with the passage 8 in said manifold. Leading from the passage 13 are smaller passages 14 and 15, the rearward extremity of the latter communicating with a nozzle 16 soldered upon the rearward extremity of said fitting. 95 Said nozzle is of a diameter slightly less than that of the rearward end of said fitting and the same is provided with lateral discharge openings 17. Threaded upon said end of said fitting is a cap 18 having a central 100 discharge opening 19 at its rearward extremity. Said opening is adapted to co-operate with the conically formed rearward extremity of the nozzle 16 so that by rotating the cap 18 upon the fitting 12 the flow 105 of gas through the opening 19 may be regulated as desired, the forward extremity of said cap being, as shown, formed for engagement by a wrench or other tool to facilitate such adjustment.

The cap 18 terminates at its rearward extremity in a mixing chamber 20 which is

constituted within a double conical casing 21, said casing being, as indicated, in communication with the pipe 22 which leads to the burner 6. Admission of air to the 5 chamber 20 is effected through an opening 23 provided in the wall 21 thereof, the passage of air through said opening being adapted to be regulated by a conical sleeve 24 rotatably mounted upon the casing 21, 10 said sleeve being provided with an opening 25 adapted to register with the opening 23. The regulation of air to the chamber 20 may evidently be effected by rotatable adjustment of the sleeve 24.

15 Slidably mounted in the upper end portion of the fitting 12 is a needle valve 26 so arranged as to be adapted when in lowered position to close the fuel passage through said fitting. Said valve is normally held in 20 lowered position by means of a compression spring 27 which is arranged within a screw cap or housing 28 threaded upon the upper extremity of said fitting. Formed within said fitting at either side of the valve 26 are 25 parallelly extending openings 29 in which are slidably mounted the upper end portions of a U-shaped member 30. The upper extremities of said member 30 are connected by means of a yoke or bar 30' with the upper 30 extremity of the valve 26 so that the operation of said valve may be effected by sliding operation of the member 30. Pivotal secured to the lower extremity of the member 30 is a depending link 31.

35 Supported centrally in the burner 6 is a disk 32 the same being locked in position therein by means of angular engaging devices 33 carried by said plate and which are adapted to be turned to engage against the 40 under side of said burner as clearly indicated in Fig. 1. Slidably mounted centrally in the disk 32 is a vertically extending rod 34 at the upper extremity of which is carried a rounded head 35 the latter being 45 adapted normally to project up through the grate 4 for engagement and depression by a utensil arranged upon the latter. The lower extremity of the rod 34 is bifurcated for engagement of the bifurcated upper end 50 portion of an extension 36 which is adjustably secured thereto by means of screws 37. Having its upper extremities secured by means of a strap 38 and bolts and nuts 39 to the pipe 22 is a depending hanger 55 40. Pivotal secured to the lower end of the hanger 40 substantially midway its extremities is a lever 41 at the respective ends of which are slidably adjustable flanged and slotted sections 42 and 43, 60 the latter being secured to the lever 41 in positions of adjustment by means of screws 44. The forward extremity of the section 42 loosely engages a slot 45 provided in the link 31 adjacent its lower extremity,

the outer extremity of the section 43 being 65 pivotally connected as at 46 with the lower extremity of the extension 36 of the rod 34.

With this arrangement it will be seen that an operative connection is established between the utensil operable presser rod 34 70 and the valve 26 whereby the arrangement of a utensil upon the grate 4 will effect the opening of said valve. Upon removal of the utensil or article from said grate, in which event the rod 34 will be released, 75 said valve will be forced to closing position and hence said valve will be forced downwardly to closing position and said rod 34 upwardly to initial position by means of the spring 27. Thus fuel will be fed to the 80 burner 6 only when an article or utensil is arranged upon the grate.

Secured upon one side of the fitting 12 is a block 47, the latter being preferably provided with a threaded nipple 48 which is 85 threaded into said fitting. Formed through said block is a fluid passage 49 which communicates with the fluid passage 13 in said fitting. A needle valve 50 threaded into the block 47 is so arranged as to be adapted to be 90 adjusted to regulate the flow of fuel through the passage 49. To the outer extremity of the passage 49 is connected a pipe 51 which extends rearwardly and terminates at its discharge end adjacent the upper side of the 95 burner 6. Said end 52 terminates in a downwardly extending manner so that grease or dirt will not be readily caught therein to effect clogging thereof. The pipe 51 bears a comparatively fine fluid passage so as to adapt 100 the same to support but a pilot light at its discharge end. With this provision the valve 9 being presumed to be open, a pilot light may be constantly burning at the burner so that when fuel is supplied to the latter in the 105 manner before described the same will be lighted so as to be utilized for heating purposes. With a device of this construction then at the commencement of the preparation of a meal it is only required to open the 110 valve 9 and to light the gas issuing from the discharge extremity of the pipe 51. In the course of the preparation of the meal with this provision, the burner will be in operation, that is, fuel will be fed thereto 115 and lighted only when an article or utensil is arranged thereon for heating. By forming the presser head 35 of rounded shape as shown and stated, provision is made whereby it is not required to place an article directly down upon the same in order to operate it but an article may be slid horizontally to position and still operate the same just as effectually. The rod 34 and the lever 41 are adjustable in their nature, as stated, 120 so as to adapt the device for arrangement upon stoves or in conjunction with burners of various designs and dimensions. The

link 31 is pivotally connected to the member 30 so that the screwing of the fitting 12 into the manifold 7 will be permitted.

While I have shown what I deem to be the preferable form of my invention I do not wish to be limited thereto as there might be various changes made in the details of construction and arrangement of parts described without departing from the spirit 10 of the appended claims.

Having described my invention what I claim as new and desire to secure by Letters Patent is:

1. The combination of a burner; a mixing chamber; a fuel supplying manifold; a pipe having one end communicating with said burner and its other end communicating with the mixing chamber; a vertically disposed fitting connecting said manifold and 15 said mixing chamber and having a passage therethrough; a vertically slideable needle valve controlling said passage; a vertically slideable U-shaped member in said fitting; a yoke connecting the upper end of the limbs of said U-shaped member with said needle valve; a cap threaded to said fitting and connecting the upper end of said needle valve and said 20 yoke; a compression spring imprisoned in said cap and arranged to hold said needle valve yieldingly to its seat; a utensil de-pressible means arranged at the burner; and an operative lever connected to said de-pressible means and said U-shaped member, the 25 connection with said U-shaped member consisting of a link pivotally connected with said member and having a slot engaging the end of said lever, substantially as described. 30
2. The combination of a burner; a mixing chamber; a fuel supplying manifold; a pipe having one end communicating with said burner and its other end communicating with the mixing chamber; a vertically disposed fitting connecting said manifold and 35 said mixing chamber and having a passage therethrough, the said fitting being threaded in the top of said manifold; a vertically slideable needle valve controlling said passage; a vertically slideable U-shaped member in said fitting; a yoke connecting the upper end of the limbs of said U-shaped member with said needle valve; a cap threaded to said fitting and connecting the upper end of said needle valve and said 40 yoke; a compression spring imprisoned in said cap and arranged to hold said needle valve yieldingly to its seat; a utensil de-pressible means arranged at the burner; and an operative lever connected to said de-pressible means and said U-shaped member, the 45 connection with said U-shaped member consisting of a link pivotally connected with said member and having a slot engaging the end of said lever, substantially as described. 50

In testimony whereof I have signed my name to this specification in the presence of two subscribing witnesses.

ROGER LOCKE AVERY.
